UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 31, 1922. Serial No. 598,066.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and particularly to the paper-handling devices thereof.

Objects of the invention are to facilitate the insertion, adjusting, typing and withdrawal of superimposed worksheets passed 15 around the platen from the introductory side thereof, particularly a wide record-sheet forming an inner sheet, a narrower ledger-sheet outward from the record-sheet, and a statement-sheet narrower than the ledger- 20 sheet and forming an outer sheet, the record-sheet to remain in the machine while different ledger-sheets and corresponding statement-sheets are successively inserted, typed and withdrawn. Another object of 25 the invention is to produce a device of the kind above mentioned, which may be readily installed upon or detached from an ordinary typewriting machine, particularly an Underwood Standard machine, without the necessity of making any substantial changes 30 in the machine as ordinarily built without the present invention.

According to the present invention, a wide record-sheet, together with its overlying 35 carbon-sheet, is inserted at the introductory side of the platen over an auxiliary paper-table, mounted in spaced relation forwardly of a main rear paper-table, and is pushed around beneath the platen, while the usual 40 feed-rolls running on the lower side of the platen are released. When the leading ends of the record-sheet and overlying carbon-sheet come up at the front of the platen, they are directed rearwardly, beneath and to the 45 rear of a front collating table, and beneath and to the rear of released paper-fingers, which, after the record-sheet has been adjusted, are made effective to hold the record-sheet, together with its carbon-sheet, against 50 the platen. A ledger-sheet and narrower statement-sheet, together with an interleaved carbon-sheet, may now be inserted over the main rear paper-table and brought up at the front of the platen, forwardly of 55 the paper-fingers, and at the front of a col-

lating table. First the ledger-sheet is adjusted relatively to the record-sheet, and a releasable clamp is made effective to engage the margin of the ledger-sheet to hold it on the collating table in adjusted position, 60 while the narrower statement-sheet is adjusted relatively thereto, after which the usual feed-rolls may be made effective, and the clamp made ineffective, whereupon typing and line-feeding of all the sheets may proceed in the usual manner. As a feature of the invention, the paper-fingers adjacent the end portions of the platen are provided at the rear thereof with side-edge gages for 65 the record-sheet, and these side-edge gages include floor-portions to support and guide the record-sheet at its margins, these paper-fingers being mounted for sliding movement lengthwise of the platen to vary the position 70 of the side-edge gages, as determined by the width of the record-sheet. As a further feature of the invention, side-edge gages for the ledger-sheet and statement-sheet are carried by the collating table, and are mounted to be adjusted different distances apart, according 75 to the width of the sheets to be gaged thereby, and the collating table, together with its side-edge gages, is mounted for sliding movement as a whole along the platen, in order to position the narrow ledger-sheet and narrower statement-sheet in different selected positions sidewise of the wide record-sheet. According to one feature of 80 the invention, the collating table and paper-fingers are mounted to be swung as a unit 85 away from the platen, to provide for the passing of the leading end of the record-sheet and its carbon-sheet rearwardly over the platen, below and to the rear of the collating table and paper-fingers. According 90 to another feature of the invention, novel means are provided for varying the pressure of the paper-fingers against the platen. According to another feature of the invention, the collating table and paper-fingers 95 are carried by a single transverse rod, detachably mounted at its ends upon the ends of the platen-frame, so that the collating table and paper-fingers may be detached from the machine as a unit. According to 100 another feature of the invention, the main rear paper-table and the auxiliary paper-table are connected together and are mounted on the platen-frame to be swung forwardly as a unit, in order to give access to parts 105 110

of the machine at the rear of said paper-table, such, for example, as the usual tabulator-stops and column-selectors. More particularly, the rear main paper-table is hinged 5 at its lower edge to the platen-frame, and the auxiliary paper-table is detachably mounted upon said main paper-table, and means are provided for releasably holding said paper-tables at their rear or sheet- 10 guiding positions.

Other features and advantages will hereinafter appear.

In the accompanying drawings.

Figure 1 is an enlarged, front-to-rear, 15 vertical section about on the line 1—1 of Figure 4, as viewed from the left, and shows the present invention as embodied in an Underwood typewriting machine, and illustrates the manner in which a ledger- 20 sheet and a statement-sheet may be inserted from the rear around the platen, outwardly of a record-sheet held in the machine.

Figure 2 is a largely diagrammatic similar view on a reduced scale, illustrating all 25 of the sheets as inserted in the machine, and the feed-rolls made effective, but with the clamp still in engagement with the margin of the ledger-sheet.

Figure 3 is an enlarged, front elevation 30 of some of the parts appearing at the right of Figure 4.

Figure 4 is a front elevation of the platen-frame, with the present invention installed thereon, and partly diagrammatic 35 and with parts broken away.

Figure 4^a is a view similar to Figure 3, illustrating modified means for releasably holding the swingable rear paper-tables at their rear or sheet-guiding positions.

40 Figure 5 is a partial top view, looking downwardly and slightly forwardly in line with the inclined front paper-table or collating table.

Figure 6 is a reduced front view of the 45 detached auxiliary paper-table.

In the accompanying drawings, the present invention is shown as applied to or embodied in a Standard Underwood typewriting machine.

50 In carrying out the invention, first there is inserted in the machine a wide record-sheet or proof-sheet 1, together with a narrower overlying carbon-sheet 2, the forward end of which, at 3, is folded rearwardly over the leading edge of the record-sheet 1 to facilitate the insertion of the carbon-sheet 2 along with the record-sheet 1, at the introductory side of a more than ordinarily long 55 revoluble platen 4, journaled by means of its axle 5 in the end walls 6 of a substantially usual platen-frame. The record-sheet 1, together with its overlying carbon-sheet 2, is passed downwardly over an auxiliary rear paper-table 7 which is spaced forwardly from 60 a main rear paper-table 8. As the record-

sheet 1 and its carbon-sheet 2 are pushed downwardly, a usual curved paper-apron 9 guides these sheets around the platen and up at the front thereof, the usual releasable front and rear feed-rolls 10 and 11 being 70 cast off, as shown in Figure 1, so as to provide a free passage for the record-sheet 1 and its carbon-sheet 2. As the leading ends of the record-sheet and its carbon-sheet come up at the front of the platen they are 75 directed rearwardly beneath a front collating table 12, which is formed in right and left sections or parts 13 and 14, and the leading ends of the record-sheet 1 and carbon-sheet 2 pass rearwardly beneath 80 paper-fingers which extend downwardly at the front of the platen above the printing line, and comprise a right-hand paper-finger 15, a left-hand paper-finger 16 and an intermediate paper-finger 17. The collating table and paper-fingers are mounted, as hereinafter to be particularly described, to swing away from the platen to provide for the leading ends of the record-sheet 1 and carbon-sheet 2 to pass freely below and to the 85 rear thereof.

The wide record-sheet 1 is gaged at its side edges by side-edge gages 18 and 19 which extend rearwardly from the upper portions of the right and left paper-fingers 95 15 and 16, respectively, and the side-edge gages 18 and 19 are respectively provided at their rear ends with inwardly-directed inclined floor-portions 20 and 21 to maintain the record-sheet between the side-edge gages 18 and 19, and also to direct the sheet upwardly and rearwardly so as to prevent it from passing backwardly around the platen. The side-edge gages 18 and 19 are bent rearwardly from outwardly-extending arms 22 and 23, to the inner ends of which the upper ends of the paper-fingers are detachably secured by means of screws 24, so that the paper-fingers 15 and 16 overlie the side margins of the record-sheet 1, while the side-edge gages 18 and 19 may project 100 rearwardly beyond the side edges of this sheet. The paper-fingers 15 and 16, together with their side-edge gages 18 and 19, are mounted, in a manner hereinafter to be 110 described, to be slidably adjustable along the length of the platen 4, as determined by the width, and desired sidewise position, of the record-sheet 1, and the intermediate paper-finger 17 is similarly slidably mounted 115 so that it may be properly positioned for holding the middle of the record-sheet against bulging away from the platen. When the record-sheet is adjusted to the typing position, the paper-fingers 15, 16 and 17, together with the collating table 12, are swung to a position to render the paper-fingers effective to press the record-sheet 1 and its carbon-sheet 2 against the platen, thereby to hold them in adjusted position. 120 125 130

While the record-sheet 1 is held in adjusted position by the paper-fingers, a ledger-sheet 25, forming an intermediate sheet narrower than the record-sheet, and 5 a statement-sheet 26, forming an outer sheet narrower than the ledger-sheet 25, together with an interleaved carbon-sheet 27, may be inserted downwardly over the main rear paper-table 8, and at their leading edges 10 brought up at the front of the platen outwardly from the paper-fingers and at the front of the collating table 12, where the ledger-sheet 25 may be gaged at either or both of its side edges by means of right 15 and left side-edge gages 28 and 29 carried respectively by the outer edges of the right and left table-sections 13 and 14, and the narrower statement-sheet 26 may be gaged by the left-hand side-edge gage 29, so that 20 the right-hand margin of the ledger-sheet 25 projects beyond the right-hand edge of the statement-sheet 26, as shown in Figure 4. By means hereinafter to be described, the side-edge gages 28 and 29 are adjustable to different distances apart, as determined by the width of the ledger-sheet 25, and also the collating table 12, which is considerably narrower than the length 25 of the platen 4, is slidably adjustable along 30 the length of the platen, by means hereinafter to be described, in order thereby to determine the desired sidewise position of the ledger-sheet 25 and statement-sheet 26 relatively to the wide record-sheet 1. 35 The ledger-sheet 25 is adjusted to typing position relatively to the record-sheet 1, while the latter is held in adjusted position by the paper-fingers, as hereinafter to be particularly described. When the ledger-sheet 25 has been adjusted, it may be 40 temporarily held in adjusted position by means of a clamp comprising a presser-block or foot 30 carried upon the inner end of a bent lever 31, fixed upon a shaft 32, 45 journaled at its ends in a bracket 33, which is secured to the outer side of the right-hand side-edge gage 28 of the right-hand section 13 of the collating table 12. The presser-block 30 is releasably held in either 50 its effective or ineffective position by a spring 34, connected to the bracket 33 and to an outwardly-projecting arm 35 of the lever 31, the spring 34 exerting its tension at one side of the shaft 32 in the effective 55 position of the presser-block 30, and at the other side of the shaft in the ineffective position of the presser-block. While the ledger-sheet 25 is held in adjusted or typing position by the presser-block 30 of the 60 clamp, the narrow statement-sheet 26 may be adjusted relatively to the ledger-sheet 25, whereupon the feed-rolls 10 and 11, which run upon the lower side of the platen, may be made effective, as shown in Figure 2. 65 The above-described clamp for holding the ledger-sheet 25 may now be released, and typing upon all of the sheets may proceed in the usual manner, all of the sheets being line-spaced together, which may be effected by rotating the platen, either by 70 means of finger-wheels 36 upon the ends of the platen-axle 5, or by means of the usual Underwood or any suitable line-spacing mechanism, of which a line-space ratchet-wheel 37 is shown upon the platen-axle 5 at the left in Figure 4. The carbon-sheet 2 for the wide record-sheet 1 is narrower than the record-sheet, being only of a width suitable for reproducing upon the record-sheet the entries made upon the ledger-sheet, so that the record-sheet 1 may have a comparatively wide side margin projecting beyond the ledger-sheet 25 and carbon-sheet 2 for receiving additional data, such as the name of the customer, which 80 it is desired to have upon the record-sheet and not upon the statement-sheet nor upon the ledger-sheet, as is shown in Figure 1. This exposed marginal part of the record-sheet 1 appears in the drawings at the right-hand end of the platen, but, by sliding the collating table 12 along the platen 4, as hereinbefore mentioned, the margin for additional data could appear at the left-hand side of the record-sheet 1, or, if desired, the collating table could have a middle location relatively to the record-sheet, so as to provide a projecting margin at each side of the record-sheet. It is often desired 85 to have data appear upon the ledger-sheet 25 and record sheet 1 to the exclusion of the statement-sheet 26, and the margin of the ledger-sheet 25 which projects beyond the narrower statement-sheet 26 provides 90 for such additional data, as well as providing for the clamping of the ledger-sheet in adjusted position while the statement-sheet is adjusted, as hereinbefore described. 95 When the desired item or items have been 100 typed upon the statement-sheet 26 and the ledger-sheet 25, together with the typing of the corresponding additional data upon the exposed margin of the record-sheet 1, the feed-rolls 10 and 11 may be cast off, and the 105 typed ledger-sheet and statement-sheet withdrawn from the machine upwardly at the front of the platen, then, while the record-sheet 1 and its carbon-sheet 2 are held in position in the machine by means of the paper-fingers, a fresh statement-sheet and ledger-sheet, with an interleaved carbon-sheet, may be inserted in the machine over the main rear paper-table 8 in the 110 same manner as the preceding ledger-sheet, statement-sheet and carbon-sheet were inserted, so that the record-sheet 1, by means of its carbon-sheet 2, receives impressions of the matter typed upon a plurality of sets 115 of statement-sheets and ledger-sheets, 120 125 130

which successively replace each other in the machine until the record-sheet is used up, after which, of course, a new record-sheet may be inserted in the manner hereinbefore described. In order to provide for the entry of items adjacent the lower or trailing edge of the record-sheet 1 and at the same time to prevent the leading edges of the statement-sheet and ledger-sheet from catching against or fouling the trailing edge of the record-sheet, the carbon-sheet 2 for the record-sheet 1 is considerably longer than the record-sheet 1, so as to extend rearwardly beyond its trailing edge over the rear auxiliary paper-table 7, to form a guide for the leading edges of the ledger-sheet and statement-sheet below the lower edge of the auxiliary paper-table, as shown in Figure 1.

Usually all of the work-sheets are provided with ruled columns which must be brought into alignment, and this is provided for by the hereinbefore-mentioned slideable adjustment of all of the side-edge gages, as well as by the slideable adjustment as a whole of the collating table 12. In some cases, blank left-hand side margins are provided on the ledger-sheets 25 and statement-sheet 26, and, in such a case, the left-hand side-edge gage 19 for the record-sheet 1, together with the left-hand paper-finger 16, is set inwardly from or to the right of the left-hand side-edge gage 29 for the ledger-sheet 25 and statement-sheet 26, as shown at the left in Figure 4. However, in case it should be desired to provide a left-hand side margin on the record-sheet 1 to project beyond the left-hand side edges of the ledger-sheet 25 and statement-sheet 26, the left-hand side-edge gage 19 for the record-sheet 1 may be positioned outwardly or to the left of the left-hand side-edge gage 29 for the ledger-sheet 25 and statement-sheet 26, similar, in this respect, to the outward positioning of the right-hand side-edge gage 18 for the record-sheet 1 in its relation to the right-hand side-edge gage 28 for the ledger-sheet 25, as shown at the right in Figure 4. In order to provide for the convenient insertion of the ledger-sheets and statement-sheets over the main rear paper-table 8 by the use of either the right hand or the left hand, according to the position of the collating table 12 along the platen, the auxiliary rear paper-table 7, which at its lower part is of the full width or, as shown in the drawings, somewhat wider than the length of the platen, is cut away at 38 at the right and upper part thereof, to provide a space for the right hand to grasp the ledger-sheet and statement-sheet when these sheets are to be inserted around the right-hand end portion of the platen, and is similarly cut away at 39 at the upper part of the left side, to provide a similar space for the left hand to

grasp and insert the record-sheet and statement-sheet in the leftward position of the collating table 12 shown in Figure 4. In this connection, it should be noted that the main rear paper-table 8 is of a width to extend along the full length of or beyond the ends of the platen, so as to receive a record-sheet which may be of a width extending the full length of the platen, or which, if narrower, may occupy any desired position along the length of the platen, corresponding to the adjusted position of the side-edge gages 18 and 19, as shown in Figure 4.

The hereinbefore-mentioned means for mounting the paper-fingers and the collating table on the platen-frame will now be described. All of the paper-fingers and the collating table are mounted upon a rockable shaft or rod extending above the platen and in parallel relation thereto, and comprising a main or middle rod part 40 and right and left end sections 41 and 42 provided at their inner ends with similar sockets 43, in which the ends of the main rod part 40 are fixed by means of screws 44. The gage-carrying arms 22 and 23 of the right-hand and left-hand paper-fingers 15 and 16, respectively, are provided at the upper sides of their inner ends with outturned portions 45 secured by means of screws 46 to U-shaped bracket-members 47, which are slidably and rotatably mounted on the main rod part 40, and each of which is provided with a projecting finger-piece 48 by which the paper-fingers may be either slid along or rotated upon the main rod part 40. These paper-fingers may be held in adjusted positions and pressed towards the platen by means of detents 49 carried by the U-shaped members 47, and pressed by means of springs 50 into a longitudinal groove 51 in the rod part 40. The intermediate paper-finger 17 is substantially similarly mounted upon the main rod part 40 by means of a U-shaped bracket-member 52 provided with a finger-piece 53. It will be seen that the paper-fingers 15, 16 and 17, together with the side-edge gages 18 and 19 carried by the end paper-fingers 15 and 16, may be independently rotated upon the rod part 40 to effective or ineffective positions.

The collating table 12 is carried at its opposite sides by a pair of U-shaped bracket-members 54 provided with detents 55 pressed into the groove 51 of the rod part 40 by springs 56. The bracket-members 54 are provided with out-turned ears 57 upon which the ends of a cross-bar 58, upon which the collating table 12 is mounted, are secured by means of thumb-screws 59 screwing into the ears 57 and engaged by oppositely-turned bayonet-slots 60 in the bar 58, whereby, merely by loosening the thumb-screws 59, the collating table 12 may be detached as a whole when desired, for example, to give

free access to parts of the machine at the rear thereof, or for using the machine with the paper-fingers without the collating table should this be desired in any particular instance.

The right and left sections or parts 13 and 14 of the collating table 12 are secured upon the cross-bar 58 by means of screws 61 passing through transverse slots 62 in the table parts 13 and 14, thereby providing for adjustably varying the width of the collating table as a whole, and for, at the same time, adjustably varying the distance apart of the side-edge gages 28 and 29 carried by the respective table parts 13 and 14. It is to be noted that the table-carrying bar 58 is of considerably less length than the platen, and that correspondingly the collating table 12 is of much less width than the length of the platen, so that the collating table may be positioned at different places along the length of the platen, the U-shaped bracket-members 54 then sliding along the rod part 40. Also, the collating table 12 may be tilted away from the platen independently of the paper-fingers to give access to the latter, the collating table, however, being normally held in collating position by means of the spring-pressed detents 55. In order to provide space for the hand to readily grasp the upper ends of the typed ledger-sheet and statement-sheet, 25 and 26, the right and left sections or parts 13 and 14, respectively, of the collating table 12 are cut away at 63 and 64, at the top and inner edges thereof.

It is to be noted that all of the paper-fingers and the collating table are mounted upon the middle or main rod part 40. If desired, the outwardly-projecting arms 22 and 23, which carry the side-edge gages 18 and 19 for the record-sheet 1, may be made of greater length than shown in the drawings, so that the side-edge gages may be positioned beyond the sockets 43 at the extreme ends of the platen, so as to enable the use of a record-sheet of the full width of the length of the platen. Should it be desired to leave a wide margin at the left side instead of at the right side of the record-sheet 1, the collating table 12 may be moved along the platen to the right-hand end portion thereof. When this is done, the left-hand gage-carrying paper-finger 16 may be placed upon the rod part 40 to the left or outwardly from the left-hand U-shaped bracket-member 54, similarly in this respect to the right-hand gage-carrying paper-finger 15 in its relation to the right-hand bracket-member 54. Also, in this case, if found desirable, the right-hand gage-carrying paper-finger 15 may be placed to the left or inwardly from the right-hand bracket-member 54, similarly in this respect to the left-hand paper-finger 16 in its relation to the left-hand bracket-member 54,

as shown in Figure 4. Preferably the paper-fingers which are positioned beneath the collating table are made comparatively short in order to provide for the free passage thereover, or at the front thereof, of the ledger-sheet 25 and the statement-sheet 26, and to clear the type-bars when at the printing point while the paper-finger which is to engage the record-sheet 1 alone may be of greater length, as shown in Figures 1 and 4, in which the left-hand paper-finger 16 and the intermediate paper-finger 17, beneath the collating table 12, are shown as somewhat shorter than the right-hand paper-finger 15.

The socket-forming end parts 41 and 42 of the three-part transverse rod are journaled in U-shaped bearing-forming brackets 65 and are yieldably rotatively positioned therein by means of detents 66 pressed by springs 67 into longitudinal grooves in the rod parts 41 and 42. The detents 66 co-operate with the paper-finger detents 49 to press the paper-fingers towards the platen, and also co-operate with the collating-table detents 55 for holding the collating table 12 at the collating position. The outer end of the left-hand rod section 42 has fixed thereon a finger-piece 68, by means of which all of the rod parts 40, 41 and 42 may be rocked in a counter-clockwise direction, as viewed in Figure 1, for concomitantly tilting the collating table 12 rearwardly away from the platen and raising the paper-fingers away from the platen, to provide for the insertion of the record-sheet 1, as hereinbefore described, after which the finger-piece is moved forwardly to restore the collating table 12 to its collating position and concomitantly to return the paper-fingers to their effective positions as shown in the drawings.

The U-shaped bearing-brackets 65 for the terminal rod parts 41 and 42 are mounted upon the platen-frame ends 6 by means of shouldered thumb-screws 69 passing through the bearing-brackets 65 and through base-blocks 70, and at their lower ends threaded into nuts 71 contained in undercut slots 72, which extend fore and aft in strips or plates 73, which are secured by means of screws 74 upon the tops of the platen-frame ends 6. By loosening the thumb-screws 69, the rod-carrying bearing-brackets 65 may be moved to different positions forwardly or backwardly on the platen-frame and set or fixed at the desired position by again tightening the thumb-screws 65, thereby providing for varying the tension or pressure of the paper-fingers against the platen. A small paper-holding roll 75 is provided at the upper part of each of the paper-fingers, which, in order not to interfere with the above-described adjusting forwardly or backwardly of the paper-fingers, is not

mounted directly upon the paper-finger, but is journaled upon a separate comparatively thin and easily yieldable leaf-spring 76, which, at its upper end, may be held by the 5 screws 24 which hold the paper-finger, as shown most clearly in Figure 1. The rolls 75 may project beyond the paper-fingers towards the platen through suitable openings provided in the paper-fingers. The screws 10 44, which hold the ends of the main or middle rod part 40 in the sockets 43, provide for the rotative adjustment of the main rod part 40 in the sockets for correctly positioning the collating table 12 at the proper 15 angle. This rotative adjustment of the main rod part 40 also provides additional means for adjusting the pressure of the paper-fingers against the platen, so that, by means of the two adjustments, one being 20 the rotative adjustment of the rod part 40 and the other being the fore-and-aft adjustment of this rod part by means of the thumb-screws 69, suitable adjustments of both the collating table and the paper-fingers may 25 be readily obtained. Merely by removing the thumb-screws 69, the collating table 12 and the paper-fingers 15, 16 and 17 may be detached from the machine as a unit.

The Underwood machine commonly is 30 provided with tabulator-mechanism including, at the rear of the machine, tabulator-stops 77 and column-selectors 78, and, in order to provide ready access to the tabulator-stops and the column-selectors, the rear 35 paper-tables 7 and 8 are mounted to be swung forwardly upon the platen-frame. The lower part of the main rear paper-table 8 passes downwardly above the upper part of a substantially usual lower rear paper-table 40 79, forming part of the platen-frame, and the lower part of which is continued below the lower end of the main rear paper-table 8, forming therewith a continuous paper-guiding surface, and the paper-apron 9 is shown as forming a forward continuation 45 of the lower end of the usual rear paper-table 79. The lower end of the main rear paper-table 8 is pivoted upon the lower rear paper-table 79 by means of a rod 80 50 passing through loops 81 at the back of the lower paper-table 79 and is engaged by rearwardly-turned fingers 82 on the lower end of the main paper-table 8, and which pass through openings 83 provided in the 55 usual or lower paper-table 79.

The auxiliary rear paper-table 7 is detachably mounted upon the main rear paper-table 8 by means of bracket-members 84 bent rearwardly and upwardly from the 60 ends thereof, and in their upwardly-inclined ends provided with slots 85 to receive bolts 86, which pass through the side margins of the main rear paper-table 8, whereby the auxiliary paper-table 7 is detachably mounted upon the main rear paper-table 8.

The two forwardly-swingable rear paper-tables 7 and 8 may be releasably held at their rear paper-guiding positions by means of rearwardly and upwardly extending supporting brackets 87, which, at their lower 79 and forward ends, overlie the rear ends of the slotted plates 73, and are secured to the rear part of the platen-frame ends 6 by means of the screws 74, which hold in place the rear ends of the slotted plates 73. The 75 upper ends of the supporting brackets 87 are turned inwardly at 88 to underlie the side margins of the main rear paper-table 8. Thumb-screws 89, passing rearwardly through slots 90 in the margins of the main 80 rear paper-table 8, screw into the inwardly-turned ends 88, these thumb-screws 89 being removed to enable the paper-tables 7 and 8 to be swung forwardly.

In order to avoid removal of the thumb-screws 89 and their possible loss, preferably the modified construction shown in Figure 4^a is employed. In this latter construction, a swingable clamp or button 91 is pivoted upon the upper end portion of the supporting bracket 87 and is held in place thereon by means of a clamp-screw 92, which may be tightened for clamping the adjacent margin of the main rear paper-table 8 between the inwardly-turned end part 88 of 95 the bracket-member 87 at the back and the clamp-member or button 91 at the front, so that merely by loosening the clamp-screw 92, the clamp-button 91 may be rotated to a position of disengagement from the main 100 rear paper-table 8, so as to permit it to be swung freely forward together with the auxiliary rear paper-table 7 carried thereby, as hereinbefore described.

Means, in addition to the bracket-members 105 84, are provided below these bracket-members for bracing and steadyng the lower part of the auxiliary paper-table 7, whereby it may be firmly held in place so as to keep open the throat formed between 110 its lower edge and the platen for the passage of the record-sheet 1 and its carbon-sheet 2, and also likewise to keep open the throat formed between the lower edge of the auxiliary paper-table 7 and the lower 115 part of the lower rear paper-table 79, to permit free passage of the ledger-sheet 25 and statement-sheet 26, together with the interleaved carbon-sheet 27. For this purpose, forwardly-projecting lugs 93 have 120 their rear ends turned inwardly at the rear of the auxiliary paper-table 7 at a point below the bracket-members 84, and are secured to the auxiliary paper-table 7 by means of screws 94. The forward ends of 125 the lugs 93 are provided in their lower edges with T-slots 95, which engage over shouldered thumb-screws or clamping screws 96, the threaded ends of which pass outwardly through the T-slots and are 130

screwed into upstanding brackets 97 turned upwardly from the inner edges of base plates or strips 98, which lie upon the tops of the platen-frame ends 6 beneath the slotted plates 73, the bracket-providing plates 98 being secured upon the platen-frame ends by the screws 74 for the slotted plates 73.

Preferably the lower margin of the auxiliary paper-table 7 is strengthened by means 10 of a transverse offset portion 99. When the rear paper-tables 7 and 8 are to be swung forwardly, the thumb-screws 96 are merely loosened sufficiently so that the upper ends of the T-slots 95 may move forwardly on the screws. In case the auxiliary rear paper-table 7 is to be detached, the T-slots 95 provide for the free lifting away of the table when the thumb-screws 96 are loosened. It will now be clear that 15 the present invention may be readily embodied in a Standard Underwood typewriting machine, so as to adapt it for doing the class of work hereinbefore described.

Variations may be resorted to within the 20 scope of the invention, and portions of the improvements may be used without others.

Having thus described my invention, I claim:

1. In a typewriting machine, the combination with a revoluble platen, of a paper-table at the introductory side thereof for guiding work-sheets to the platen, an auxiliary paper-table for guiding an inner work-sheet to the platen clear of the first-mentioned paper-table, supporting brackets extending rearwardly from the auxiliary paper-table, means detachably connecting the supporting brackets rigidly to the first-mentioned paper-table, the two paper-tables being swingable together as a unit about a common center to give access to mechanism behind them, and means for detaining each of the paper-tables in normal operative position, the arrangement being such that each steadies and braces the other.

2. In a front-strike typewriting machine, in combination with a revoluble platen and a platen-frame therefor, a rear paper-table for guiding outer work-sheets to the platen, means for mounting the rear paper-table on the platen-frame to swing forwardly to give access to parts of the machine at the rear of said paper-table, an auxiliary paper-table for guiding an inner work-sheet to the platen, brackets rigidly supporting the auxiliary paper-table from the rear paper-table in fixed relation thereto, to swing forwardly therewith as a unit, and releasable means for holding said paper-tables at their rear or sheet-guiding positions.

3. In a front-strike typewriting machine, in combination with a revoluble platen and a platen-frame therefor having ends, a rear paper-table on the platen-frame for guiding outer work-sheets to the platen, an auxiliary

paper-table spaced forwardly from the rear paper-table for guiding an inner work-sheet to the platen, means for detachably mounting the auxiliary paper-table at corresponding points on its side margins upon the side 70 margins of the rear paper-table, and means for detachably mounting the auxiliary paper-table at other corresponding points on its side margins upon the ends of the platen-frame, whereby the auxiliary paper-table 75 may be detached from the machine.

4. In a front-strike typewriting machine, in combination with a revoluble platen and a platen-frame therefor having ends, paper-fingers extending downwardly at the front 80 of the platen, a rod carrying said paper-fingers and extending parallel with the platen, and mounts for the ends of said rod adjustable forwardly or backwardly upon the ends of the platen-frame for varying 85 the pressure of the paper-fingers upon the platen.

5. In a front-strike typewriting machine, in combination with a revoluble platen and a platen-frame therefor having ends, paper-fingers extending downwardly at the front 90 of the platen, a rod carrying said paper-fingers and extending parallel with the platen, mounts for the ends of said rod adjustable forwardly or backwardly upon the 95 ends of the platen-frame for varying the pressure of the paper-fingers upon the platen, and paper-holding rolls resiliently mounted on the paper-fingers to yield selectively thereto to provide for said adjustment 100 of the paper-fingers.

6. In a front-strike typewriting machine, in combination, a revoluble platen and a platen-frame therefor having ends, paper-fingers extending downwardly at the front 105 of the platen, a rod carrying said paper-fingers and extending parallel with the platen, mounts for the ends of said rod adjustable forwardly and backwardly upon the ends of the platen-frame for varying 110 the pressure of the paper-fingers upon the platen, a collating table mounted upon said rod at the delivery side of the platen, and means to effect rotative adjustment of said rod to vary the angular position of the collating table and also providing further 115 means for varying the pressure of the paper-fingers upon the platen.

7. In a front-strike typewriting machine, in combination with a revoluble platen and 120 a platen-frame therefor, a wide rear paper-table for guiding narrow outer work-sheets to the platen at different selected places along the width of the paper-table and length of the platen, a wide auxiliary paper-table at the front of the rear paper-table for guiding a wide inner work-sheet to the introductory side of the platen, a narrow front paper-table above the platen at the delivery side thereof and spaced there- 125 130

from for the reception of said narrow outer work-sheets, means for mounting said front paper-table on the platen-frame to be slidably adjustable along the platen, so as to expose a margin of said inner wider work-sheet at either side of the narrow outer work-sheets received upon said front paper-table, and means for guiding said inner wider work-sheet beneath and to the rear of said front paper-table, said auxiliary paper-table being cut away at each side of the top thereof, to provide spaces enabling said narrow work-sheets to be grasped and inserted by either the right or the left hand dependent upon the position of adjustment of said narrow front paper-table along the length of the platen.

8. In a front-strike typewriting machine, in combination with a revoluble platen and a platen-frame therefor having ends, a rod extending along the top of the platen parallel therewith and having a longitudinal groove therein, paper-fingers at the front of the platen above the printing line, a mount for each paper-finger slidable on said rod for adjusting the paper-finger along the platen, and rotatable on said rod to enable the paper-finger to be rocked upon the rod between effective and ineffective positions, said mount including a spring-pressed detent engageable in said groove for controlling the normal position of the paper-finger relative to the rod and for yieldingly pressing the paper-finger towards the platen, a front collating table above the platen and paper-fingers, mounts for the collating table slidable on said rod to enable the collating table to be moved along the platen, and rotatable on said rod to enable the collating table to be tilted away from the platen, said mounts for the collating table including spring-pressed detents engageable in said groove for holding the collating table at its collating position adjacent the platen and the paper-fingers, rod supports rotatably mounted upon the ends of the platen-frame, said supports including detent-devices for controlling the normal rotative positions thereof, means for making the rod fast to the supports in various angular relations thereto to adjust the normal relation of the fingers and table to the platen and a finger-piece for rocking the supports and said rod to tilt the collating table and the paper-fingers as a unit away from the platen.

9. In a typewriting machine, the combination with a revoluble platen, of paper-

fingers to hold work-sheets against the platen, a support for said paper-fingers, means to adjust said paper-finger support bodily over the platen, detents controlling the normal angular relation of the paper-fingers to their support, and means to adjust the support angularly to cause the detents to maintain the paper-fingers normally in co-operative relation to the platen when the support has been bodily adjusted.

10. In a typewriting machine, the combination with a revoluble platen, of a paper-table at the front thereof, a paper-table support adjustable bodily over the platen to adjust the paper-table forwardly and rearwardly, and means for angularly adjusting the table support to procure the desired relation of the paper-table to the platen corresponding to the bodily adjustment thereof.

11. In a typewriting machine, a revoluble platen, a paper-table at the front thereof, a rod on which the paper-table is rotatably mounted, means determining a normal relation of the table to the rod, a rotatable support on which the rod is fixedly mounted, means controlling the normal rotative position of the support, and means for adjusting the rod relatively to its support to change the normal position of the paper-table obtained with the support in its normal position.

12. In a typewriting machine, a revoluble platen, a paper-table at the delivery side thereof, and means for adjusting the paper-table from side to side of the platen, bodily in a front and rear direction over the platen, and angularly about an axis parallel to the platen.

13. In a typewriting machine, the combination with a revoluble platen, of means for collating two outside sheets with reference to each other and to an underlying inside sheet, comprising feed-rolls acting exclusively on the underlying inside sheet at the front of the platen, adjustable side guides for said inside sheet at the front of the platen, a collating table between said side guides having side-edge gauges for the wider of the outside sheets, and a clamp on said collating table for detaining the wider of the outside sheets stationary in adjusted position during relative adjustment of the narrower outside sheet thereover.
